NOSE RING FITTING APPARATUS

Rudolf Hauptner, Berlin, Germany

Application August 9, 1930, Serial No. 474,289,
and in Germany August 27, 1929

6 Claims. (Cl. 128—332)

This invention relates to a device for fitting nose rings to cattle without necessity for preliminary perforation of the part of the nose separating the nostrils.

5 The primary object of the invention is to render the fitting of these nose rings a safer and more simple operation for the veterinary surgeon performing the same.

In particular it is an object of the invention 10 to enable the dividing portion of the animal's nose to be pierced at the correct point with a preparatory squeezing or holding thereof under the clamping action of a gripper. The new form of gripper possesses two semi-circular jaw portions having accurate channels or ring guides for supporting the nose ring to be applied, and on the ends of the said curved portions or jaws opposed supporting or gripping faces, the moving together of which permits of a clamping effect being exerted on both sides of the dividing portion of the nose. The gripper also possesses an operable lever, which is rotary about the centre point of the jaws moved together over a circular path, for advancing and causing penetration on the part of the ring.

An additional point of novelty associated with the present invention consists in the particular embodiment of the ring as adapted to the said gripper, the arrangement being such that the 15 hinge connection, which is provided to make the ring of a folding nature in the manner known per se, does not (as in the case of the known construction) divide the ring into two exact halves, but is so arranged that the one folding portion extends for less than half of the complete distance, i.e., forms a shorter segment than the other segment. In this manner the manipulation of the gripper upon the application of the ring is a very considerable improvement 20 as compared with the known type of ring divided into two equal halves, as under these circumstances the piercing action of the pointed section of the ring, which projects to a certain extent beyond the dividing portion of the nose, is rendered possible in one single operation, it being not until this action has been completed that the operable lever strikes against a stop. The other segment of the ring may then be folded over on to the pointed end, which projects 25 to a sufficient extent out of the nostril, and secured in the closed position before the gripper is opened and the ring released.

Up to this point, i.e., during the complete operation of fitting the ring and also the operations preparatory thereto, the animal is held by

means of the gripper, the supporting members on the ends of the jaw portions firmly holding the dividing portion of the animal's nose between them.

The invention will now be described more fully 60 with reference to the accompanying drawing, which illustrates by way of example one possible form of embodiment of the ring-fitting device with appertaining ring.

Fig. 1 is a view of the gripper with jaws moved 65 apart, the ring being shown in the opened condition and mounted on the one side, with the pointed segment partly in the advanced position as in the fitting operation.

Fig. 2 shows the gripper when closed, in which 70 connection it may be assumed that the dividing portion of the animal's nose is situated between the ends of the two jaws, the pointed piercing segment of the ring, however, still being withdrawn within the left hand jaw of the gripper, 75 with the lever (shown on the right) in the initial position preparatory to the piercing action.

Fig. 3 shows the position of the parts after 80 completed operation, the lever having been moved fully over towards the left.

Fig. 4 is an elevational view showing that the lever is oscillatory in a plane disposed laterally to the gripper and disposed freely for ready manipulation.

Figure 5 is a view of the nose ring used in the 85 device.

In the drawing the gripper having the two semicircular jaw portions *a* and *b* is shown having the two handles broken off, these not being essential for the description. The one jaw *a* 90 is furnished with an abutment plate *f* extending towards the centre. Both jaws are made in channel form by reason of flange caps *p*, *q* flanking the circular edges provided with extensions or abutments *p'*, *q'* respectively at their ends, so that said flange caps are open towards the inside, from which direction the ring may be introduced in position. The positioning of the ring in the jaws, which in their entirety are of circular form, takes place with the jaws open, 100 as shown in Fig. 1, the ring *r*', *r*'' being introduced at *p* and slid round, whereby the segment *r*'' is as a preliminary step folded back in order to uncover the pointed segment *r*'. The jaws *p* and *q* do not require to be channel-shaped in 105 their rearward portions, as at this point the ring *r*', *r*'' should be borne freely. The jaws, at their front or nose gripping ends, however, provide arcuate ring guides opening inwardly of the arc for receiving portions of the ring segments near 110

their open ends. The facing ends of these ring guides are shaped to provide appropriate nose gripping portions $p'q'$.

The nose ring, the unequal divisioning of which at the hinge portion is readily discernible in the drawing, is, when placed in position, supported radially by an offset portion i of a lever h which is pivoted at z on the plate extension f about the center point of the circular configuration established by the jaws when closed. Said offset portion of the lever h carries a stud j projecting radially inward toward the ring, one segment of which is furnished in its periphery with a hole or recess, as shown in section in Fig. 1. The lever h is offset, as at i , from the plane of the jaws, as shown in Fig. 4, to permit of unobstructed manual manipulation thereof, viz., from the position shown in Fig. 2 at one side of the jaw connection or pivot o into an opposite extreme position at the other side of pivot o , as shown in Fig. 3. The intermediate position according to Fig. 1 is the preferable one for introducing the ring into the gripper. Immediately the stud on the lever h has been moved into engagement with the hole or recess in the ring, the latter is securely held in the guide in a relative position to the lever h , so that accordingly the ring segment r^2 may be moved into the open position (as shown in the drawing) for the purpose of uncovering the piercing segment r' .

To withdraw the piercing segment into a covered position it is, as preparatory step, also necessary to move the lever h towards the right into the extreme position as shown in Fig. 2. By reason of the stud engagement at j the ring will be moved about a circular path in such manner that the pointed end thereof comes to rest within the jaw p and no longer projects beyond the end p' of said jaw. The apparatus is now ready for use, and by applying the ends of gripping portions p' and q' of the jaws p and q respectively to the division of the animal's nose may be securely held in position by the application of pressure to the gripper handles. This position is illustrated in Fig. 2. In order to ensure temporary location of the lever h and accordingly of the ring in the proper position, there is provided to the side of the stop u for the ring a projection v on a resilient lug w . This projection is capable of engaging with a hollow or recess on the underside of the lever h , a locking mechanism under frictional action thus precluding possibility of accidental movement.

When the apparatus in the position according to Fig. 2 has been applied to the animal's nose, the fitting of the ring in the nose may be readily performed by moving over the lever h out of the right hand position towards the left until—in the position according to Fig. 3—the same thrusts against the jaw p . Upon this movement the ring is caused to move over a circular path and pierce the division between the nostrils, the same being advanced to such extent that it projects out of the nostril (Fig. 3). The ring segment r^2 is then folded over into the original position on the segment r' for making the ring complete, the parts being secured in the known manner by means of a screw or the like. With part backward rotation of the lever h towards the initial position (Fig. 1) the gripper thereupon merely requires to be opened to

enable the fitted ring to be released therefrom and the gripper removed.

To prevent the lever h from moving accidentally out of the extreme position when the ring is being closed, it is preferable to provide a similar arrangement as used on the opposite side (Fig. 2). For example a stud or projection y may be provided on the jaw p capable of engaging with a recess on the underside of the lever h .

The apparatus according to the invention as described in the above offers in use one important advantage consisting in the fact that the whole operation may be performed by the veterinary surgeon in reliable manner without necessity for changing his instruments, it being possible for example for the handles of the gripper to be held with the left hand and the lever manipulated with the right hand.

The unequal divisioning of the folding ring has the advantage that, on account of the longer segment r^1 , the latter may be advanced to a relatively great extent before the lever h moves against the stop. For this reason after the division of the nose has been pierced the end 100 of the ring will project to a relatively wide extent out of the nostril, permitting the shorter segment r^2 to be readily folded over thereon into the closed position.

It will be understood that no restriction is 105 made to the specific form of embodiment shown, and that various modifications are quite possible within the meaning of the above description and the annexed claims without departing from the spirit of the invention.

What I claim as new and desire to secure by Letters Patent is:

1. An animal ringing device, comprising opposed jaws for gripping an animal prior to ringing, and means for forcing a ring from one 115 jaw to the other through the gripped part of the animal.

2. An animal ringing device comprising opposed jaws for gripping an animal prior to ringing, ring guides on said jaws, and means for forcing a ring from one guide to the other through the gripped part of the animal. 120

3. An animal ringing device, comprising opposed jaws for gripping an animal prior to ringing, curved ring guides on said jaws, and means movable in a curved path for forcing a ring from one guide to the other through the gripped part of the animal. 125

4. An animal ringing device, comprising opposed jaws for gripping an animal prior to 130 ringing, a ring guide on one of said jaws, and means carried by the same said jaw for forcing a ring through the gripped part of the animal.

5. An animal ringing device, comprising opposed jaws for gripping an animal, a curved 135 ring guide on one of said jaws, a lever pivoted to the same said jaw, said lever being engageable with an open ring to force one end thereof through the gripped part of the animal.

6. An animal ringing device, comprising opposed animal gripping jaws, ring guides on said jaws, and means for forcing one end of an open ring through the gripped part of an animal to a point where the ends of the ring are accessible 140 for being closed together. 145
